JOHN P. DORAU, OF PORTAGE, WISCONSIN

FOLDING IRONING TABLE

Application filed February 13, 1932. Serial No. 592,676.

This invention relates to improvements in folding ironing tables.

It is one of the objects of the present invention to provide an ironing table which, when in use, will be supported very rigidly and firmly, with the rigid supporting means being disposed below that portion of the table subjected to the greatest pressure in use, but which table may be easily and quickly collapsed to a compact position so as to occupy a minimum amount of storage space when not in use.

A further object of the invention is to provide a folding ironing table supported by a pair of connected legs and a third leg, all connected with intermediate portions of the table and arranged so that in collapsed position the third leg will fold in the direction of folding of the pair of legs and to be arranged compactly with respect thereto.

A further object of the invention is to provide a folding ironing table of the class described wherein the pair of legs is provided with means for diverging and spreading the same under tension when the pair of legs are in unfolded position.

A further object of the invention is to provide a folding, three-legged ironing table in which the legs and brace members therefor are all operatively connected so that a movement of one of said members will tend to move the others of said members also.

A further object of the invention is to provide a folding ironing table provided with quickly manipulable means for locking all of the legs in unfolded position.

A further object of the invention is to provide a folding ironing table which is of very simple construction, is easily manipulated, is relatively inexpensive to manufacture, is strong and durable, and is well adapted for the purposes described.

With the above and other objects in view, the invention consists of the improved folding ironing table, and its parts and combinations as set forth in the claims, and all equivalents thereof.

In the accompanying drawing in which the same reference characters indicate the same parts in all of the views:

Fig. 1 is a side view of the ironing table in open or unfolded position;

Fig. 2 is an inverted plan view thereof;

Fig. 3 is an inverted plan view of the ironing table in folded or closed position;

Fig. 4 is an end view of the ironing table in open position;

Fig. 5 is an end view illustrating a slight modification of the ironing table construction; and

Fig. 6 is an enlarged fragmentary detail sectional view taken on line 6—6 of Fig. 5.

Referring now to the drawing and particularly to Figs. 1 to 4, inclusive, thereof, it will appear that the numeral 8 indicates the board or table portion of the folding ironing table and the same may be of any suitable shape, but is preferably of rectangular form with a tapered end portion 8'.

An elongated U-bracket 9 is secured transversely to an under, intermediate portion of the board, and there is also secured to an under surface of the board transversely thereof and longitudinally removed from the bracket 9 in the direction of one end of the board, a short U-bracket 10. Another short U-bracket 11 is secured to the under surface of the board in longitudinal spaced relation to the bracket 9 between the latter and the tapered end portion 8' of the board.

For the purpose of assisting in the support of the board 8 a leg member 12 is provided, composed of a pair of members 12' secured together at their lower or outer ends and diverging upwardly, the upper end portions of said members 12' being pivotally attached to opposite end portions of the bracket 10 as at 13 and 13'.

The board is also supported by a pair of somewhat longer legs 14 which are pivotally secured at their upper end portions to opposite end portions of the bracket 9. The upper end portions of said legs 14 are beveled, as at 14', so that when said legs are unfolded with respect to the board said beveled ends will bear flatly against the under surface of the board, providing a steady support and limiting the opening or unfolding movement of said legs.

The two legs 14 are connected by means of

a pair of medially crossed brace rods 15. The lower or outer ends of the brace rods are pivotally secured to lower portions of the legs 14 as at 16 while the upper or inner end portion of each brace rod 15 has a slidable engagement with an upper or inner end portion of an opposed leg 14. Said sliding engagement is effected by means of a staple 17 secured to the leg 14 and through which the upper or inner end portion of the rod 14 passes, the extremity of the rod being formed with a hooked end portion 18 to prevent withdrawal of the same from the staple 17, as shown in Fig. 1.

15 The pair of legs 14—14 is connected with the single leg 12 by means of an elongated V-shaped wire or flexible brace 19. The outer or free end portions of said brace 19 are bent angularly and are pivotally extended through lower portions of the legs 14. The inner end portion of said brace 19 is formed with a transverse portion 19' which is pivotally extended through spaced eyelets 20 secured to intermediate portions of the members 12'. The outer recessed or slotted end portion 21 of a board brace and locking member 22 is adapted to coact in open position of the ironing board, with the transverse end portion 19' of the flexible brace 19. The opposite end portion of said board brace or locking member 22 is pivotally carried by the bracket 11. Links 23 have their upper or inner ends pivotally connected to opposite sides of the upper portion of the member 22, while the lower or outer end portion of said links 23, which are diverging, are pivotally secured to inner side portions of the legs 14 intermediate the ends of said legs.

40 When the table is folded, the parts are arranged as shown in Fig. 3 with all of the legs and pivotal braces extended in the same direction and compactly against the under surface of the board. To open or unfold the table, the leg 12 is moved away from the board, and inasmuch as said leg is connected to the transverse end 19' of the flexible brace 19, which brace is in turn connected with the pair of legs 14, when the leg 12 is unfolded, the legs 14 will also be moved away from the board toward open supporting position. During this movement the free slotted end portion 21 of the board brace and locking member 22 will be drawn along the under surface of the transverse portion 19' of the brace 19 and may ultimately be snapped into engagement with said portion 19', the said portion 19' then lodging within the recess 21 formed on the inner face of the board brace and locking member 22. During unfolding movements of the legs the crossed brace wires 15 will have their upper end portions drawn inwardly with respect to the staples 17 on the legs 14 until the hooked end portions 18 engage said staples as shown in Fig. 4. Also, unfolding movement of the leg 12 will force

the board brace 22 away from the inner face of the table and this will cause pivotal movement of the links 23 which will serve to diverge the lower end portions of said links and spread the legs 14 so that when said legs are in final open position they will be secured in open diverged position under tension. To fold the ironing board from the position illustrated in Fig. 1 it is only necessary to press against the lower outer end of the board brace and locking member 22 so as to lower the same away from the transverse portion 19' and then by folding the leg 12 inwardly the other parts will be collapsed in a manner reverse to that previously described and against the inner surface of the table or board 8 in the manner shown in Fig. 3. In folded position the free end of the board brace 22 is swung slightly to locate it under the extension of the long pivot stud 13' to aid in retaining the parts in folded positions.

15 In Figs. 5 and 6 a modification of the invention has been illustrated and in this form the crossed braces 15' are each formed in two pivotally connected sections. The lower end portion of each main section 15' is pivotally connected to a lower end portion of a leg 14 while the upper end portion of each main brace portion 15' is pivotally connected with a link 25. Each link is in turn pivotally connected with the upper end portion of an opposite leg 14 and the links 23' which extend from the board brace and locking member 22 have their outer diverged end portions pivotally connected to the connected ends of the members 15' and 25, as at 26, as best shown in Fig. 6. This arrangement precludes the necessity of having sliding connections between ends of the braces for the legs 14 and the legs, inasmuch as when the table is in folded position the connected members 15' and 25 fold with respect to each other and thus permit the legs 14 to be drawn together. In unfolded or open position of the table movement of the links 25 is limited by engagement with stops 27 projecting from upper face portions of the legs 14.

105 From the foregoing description it will be seen that the improved ironing table is of simple and novel construction and is well adapted for the purposes described.

110 What is claimed as the invention is:

1. An ironing table, comprising a board member, a pair of legs pivotally connected to the bottom portion of the board member intermediate its ends, a third leg pivotally connected to the bottom portion of the board adjacent one end thereof and remote from the pivotal connections for the pair of legs, a brace member extended between a bottom portion of the board and said third leg, said brace member being pivotally connected at one end to one of the elements between which it is extended and having its free end releasably connectible to the other of said ele- 120

130

ments, a flexible brace member extended between the pair of legs and the third leg to cause joint movement of all of said legs to and from folded position, and diverging means pivotally connected to the first-mentioned brace member and to the pair of legs and exerting leg spreading forces on the pair of legs.

2. An ironing table, comprising a board member, a pair of legs pivotally connected to the bottom portion thereof, a third leg also pivotally connected to the bottom portion of the board remote from the pivotal connections of said pair of legs, a board brace member extended between a bottom portion of the board and said third leg, said brace member being pivotally connected at one end to one of the elements between which it is extended and having its other end free in inoperative position but releasably engageable in operative position with the other of said elements, brace members extended between said pair of legs, one pair of ends of said brace members being pivotally connected with said legs and the other pair of ends of the brace members being shiftably associated with said legs whereby the outer ends of said legs may converge when folded to inoperative position against the board member, a flexible brace member extended between the pair of legs and the third leg to cause joint movement of all of said legs when moved to and from folded position, and connections between said board brace member and the pair of legs for diverging the latter when the same are moved to supporting position.

3. An ironing table, comprising a board member, a pair of legs pivotally connected to the bottom portion thereof, a third leg also pivotally connected to the bottom portion of the board, a flexible, V-shaped brace member connected at its closed end with said third leg and having its other end portions pivotally connected to the pair of legs, a board brace pivotally connected at one end to the bottom portion of the board and having its other end portion releasably engageable with the closed end of said V-shaped brace member for locking purposes when the legs are in operative position, brace members extended between said pair of legs, one pair of ends of said brace members being pivotally connected with said legs and the other pair of ends of the brace members being shiftably associated with said legs, and connections pivotally connected between said board brace member and the pair of legs for diverging the latter when the same are moved to operative position.

4. An ironing table, comprising a board member, a pair of legs pivotally connected to the bottom portion thereof, a third leg also pivotally connected to the bottom por-

tion of the board, a flexible, V-shaped brace member connected at its closed end with said third leg and having its other end portions pivotally connected to the pair of legs, a board brace pivotally connected at one end to the bottom portion of the board and having its other end portion releasably engageable with the closed end of said V-shaped brace member for locking purposes when the legs are in operative position, two pairs of foldably connected crossing braces arranged with the end portions of each pair pivotally connected to the individual legs of said pair of legs, and outwardly diverging links pivotally connected at their inner ends to said board brace member and having their outer ends pivotally connected with the crossing braces at the points of folding of the same.

In testimony whereof, I affix my signature.

JOHN P. DORAU.
